US00D733145S

(12) **United States Design Patent**
Chen et al.

(10) **Patent No.:** US D733,145 S
(45) **Date of Patent:** ** Jun. 30, 2015

(54) **MEMORY MODULE**

(71) Applicant: **KINGSTON DIGITAL, INC.**, Fountain Valley, CA (US)

(72) Inventors: **Yu-Hau Chen**, Hsinchu (TW); **Yi-Ting Lin**, Hsinchu (TW); **Chi-Hsien Huang**, Hsinchu (TW); **Peter Leekuo Chou**, Fountain Valley, CA (US); **Yu-kuo Huang**, Hsinchu (TW)

(73) Assignee: **Kingston Digital, Inc.**, Fountain Valley, CA (US)

(**) Term: **14 Years**

(21) Appl. No.: **29/485,073**

(22) Filed: **Mar. 14, 2014**

(51) LOC (10) Cl. **14-02**

(52) U.S. Cl.

USPC **D14/435**; D14/436

(58) **Field of Classification Search**

(57) **CLAIM**

We claim the ornamental design for a memory module, as shown and described.

DESCRIPTION

FIG. 1 is a perspective view of a memory module showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Broken lines and entirely unshaded portions contained within broken lines are not claimed.

1 Claim, 4 Drawing Sheets
